1,934,398

MANUFACTURING OF YARN

Aaron Benowitz, New York, N. Y., assignor to
Synthetic Fur Mills Corp., New York, N. Y., a
corporation of New York

Application November 7, 1931. Serial No. 573,582

4 Claims. (Cl. 28—62)

This invention relates to a discovery of a new and useful method or process, having for its general object to provide different kinds of yarn, as, for instance, a chenille, cords, and threads of an exterior fluffiness, with a surface that may be varied in form, character and appearance, according to the special treatment applied thereto.

As stated, generally most kinds of yarn may form the subject matter of such a treatment, whether the said yarn consists of a woolen, worsted cotton, rayon, or any other material. Thus as a suitable example, and for the purpose of illustration, a chenille may appropriately be chosen herein as the subject to which the said process is applied.

The process referred to consists primarily in the application of heat in one form or another to such yarn or chenille; thus the said heat may be applied by means of metal plates, compartments, tubes, or in any other suitable manner, while the source of the heat may naturally also be of varied kinds.

Reserving to myself the right to the exclusive use of the different forms by means of which to administer the desired treatment to the said yarn, I have herein confined myself to show but one specific form, that of a tube system, as the underlying principles would be substantially the same in all of them.

One of the main objects aimed at through the said treatment is to provide a yarn, or chenille with a surface or pattern that will have the nap or fibres arranged in a curling or swirling manner, running uniformly through the length of the said yarn, or being disposed at intervals, according to the varied forms of the treatment applied. In a similar way other kinds of surfaces or patterns may be formed upon the said yarn.

It is in this connection desired to point out that, while I refer to yarns in a general way, the principles of this invention or process may well find application on a larger scale, such as to manufacturing of allied goods; and I desire, therefore, to reserve to myself all rights in this respect.

The arrangement, relative to the process, as herein described, and exemplified by the tube system, may be accomplished or worked by hand, or may lend itself to the operation and regulation by machinery.

With the above and other objects in view, this invention consists of the novel features, combination of steps and relevant construction, as hereinafter fully described, claimed and illustrated in the accompanying drawing forming part of this application, and in which similar charac-

ters of reference indicate corresponding parts in all views, and in which:—

Figure 1 illustrates a yarn, or chenille in its usual and ordinary marketable form; while Figure 2 is a cross sectional view of same.

Figure 3 shows a chenille, which has been submitted to a treatment, according to this invention; and Figure 4 is a cross section of Figure 3.

Figure 5 is a longitudinal sectional view of a tube with a smooth inner surface, as used in this process.

Figure 6 is a similar view of a tube, having a threaded inner surface.

Figure 7 is a similar view as Figure 5, but with a partly threaded and partly smooth inner surface.

Figure 8 is another view similar to Figure 5, but the said tube is herein, as a further modification, formed with a knurled inner surface.

Figure 9 is an elevational view of a tube, showing the chenille entering the tube, or before the treatment; and leaving the tube, or after the treatment has been applied thereto, in this instance by means of the tube system, which system in the above figures has been shown in a few modified forms.

Referring more particularly to the drawing, a chenille-yarn in its usual form has been shown in Figure 1, while the chenille-yarn is shown in Figure 3 after it has been submitted to a treatment, according to this invention.

The said treatment consists in the following steps:

A piece of ordinary chenille is submitted to a heating process. Although, as previously stated, the said heating may be imparted to the yarn in different ways, the preferred embodiment for this purpose is an enclosure, or, more specifically as shown herein, a tube 10, which is heated uniformly or sectionally to such an extent that the inner surface thereof will radiate a fair amount of heat to an object placed therein, or within the said tube; the amount of heat to be given off by the said inner surface to be varied according to the purpose at hand.

The inner surface of the said tube may have various forms or impressions made thereon, as shown in Figures 5, 6, 7 and 8, in order to impart different patterns to the yarn treated.

The said tubes are heated preferably by electricity, and in a manner similar to that employed in flatirons; thus Figure 5 shows an electric contact 11, for the purpose of conveying heat to the said tube.

The yarn in its ordinary form is brought in

contact with the heating medium, or, as herein illustrated especially in Figure 9, a tube; and the said yarn is held in close proximity to or retained in and by the said tube a short length of time, for instance a few minutes, the said time naturally to be varied according to the purpose at hand and the amount of heat applied thereto.

When the yarn or chenille enters the said tube the outer ends of its fibres contact with the inner 10 surface of the tube and usually the said yarn or chenille is then submitted to a back and forward movement for a very short length of time, whereby the said yarn upon leaving the tube, as shown in Figure 7, has received a surface with a solid 15 impression, form, or a pattern, made thereon by means of the said exposure to heat in conjunction with the said contact of its fibres with the specially formed inner surface of the tube.

The object thus achieved is the result of the 20 fibres of the yarn contacting with the inner surface of the tube and of the simultaneous exposure to heat thereof. The said yarn may thus receive an appearance of, for instance, a swirled or curled form, according to the prearranged 25 design of the said inner tube-surface.

Referring to the feeding of the yarn to the said tube and the relative back and forward movement of the former, this may be accomplished by hand or by having suitable machinery connected to the 30 said heating chambers or tubes. The latter, of course, may be of any size, suitable to the purpose at hand, and, while the said yarn may be

made to move back and forth in the said tubes, the latter may be made to perform this action, while the yarn may remain stationary.

It is obvious that changes may be made in the form, construction and arrangement, as shown, within the scope of the appended claims, without departing from the spirit of the invention, and I do not therefore desire to limit myself to the manner, construction and arrangement shown and described herein.

Having thus described my invention, what I claim as new and desire to secure by Letters Patent of the United States, is:

1. A means for imparting to a yarn a special form, comprising a heated tube, movable back 90 and forth, the said tube being formed with a threaded inner surface.

2. A means for imparting to a yarn a special form, comprising a heated tube, movable back 95 and forth, the said tube being formed with an inner surface threaded at intervals.

3. A means for imparting to a yarn a special form, comprising a heated tube, movable back and forth, the said tube being formed with a knurled inner surface.

4. A means for imparting to a yarn or chenille a special form, comprising a heated tube formed with a threaded inner surface and adapted to permit a back and forth movement of the said yarn therein.

AARON BENOWITZ.
